FIG. 7.

UNITED STATES PATENT OFFICE.

JOHN C. HEINRITZ AND JAMES W. McCUEN, OF BALTIMORE, MARYLAND, ASSIGNEES OF ONE-THIRD TO RICHARD H. JOHNS, OF BALTIMORE, MARYLAND.

INCANDESCENT VAPOR-BURNER.

No. 888,707.

Specification of Letters Patent.

Patented May 26, 1908.

Application filed November 20, 1907. Serial No. 403,008.

To all whom it may concern:

Be it known that we, JOHN C. HEINRITZ and JAMES W. McCUEN, citizens of the United States, residing at Baltimore, in the State of Maryland, have invented certain new and useful Improvements in Incandescent Vapor-Burners; and we do hereby declare the following to be a full, clear, and exact description of the invention, such as will 10 enable others skilled in the art to which it appertains to make and use the same.

In a patent granted to us April 9, 1901, and numbered 671,884 for incandescent vapor burner, the gas generator body is formed 15 in a solid head the upper portion of which is heated by supplemental burners opening outside at the top of said generator and supplied with the combustible vapor by ducts formed therein and which are supplied by perforations in the mixing tube by communicating 20 with the ducts. But in using the burner the perforations in the mixing tube and the communicating ducts become filled with a gummy product the result of the vaporization 25 of the oil in the ducts, and as a result the supplemental burners failed to be supplied and to provide the necessary heat to maintain the generation of the gas from the liquid hydrocarbon to supply the burner. Another 30 objection was the insufficient capacity of the burner chamber to supply the proper volume of combustible vapor to the burner by reason of the extension of the mixing tube to the top of the solid burner head. Another objection 35 was taking the vapor direct from the mixing tube to supply the ducts for the exterior supplemental burners because the air and gas was not sufficiently mixed in the tube to supply the required quantity to give 40 the required heat to the supplemental burners and for these reasons the burner failed to give satisfaction in use. The distance the hydrocarbon fluid had to travel through the generator in its passage to be reduced to vapor was also found to be objectionable because it tended to the deposits of carbon in the ducts and because the generator could not be maintained at a uniform heat.

Our present improvement is directed to a 50 construction whereby the above noted objections are avoided and in the claim appended hereto we will point out the precise

construction which constitutes our improvement in connection with the accompanying drawings, in which,—

Figure 1 is a vertical section of an incandescent vapor lamp embodying our improvement and showing the oil inlet tube. Fig. 2 is a like section taken through the vapor supply pipe. Fig. 3 is a side view showing the fluid receiving duct and the vapor delivering duct in the generator. Fig. 4 is a horizontal section on the line 4—4 of Fig. 3 showing the supplemental external jet burners 13 in the generator head. Fig. 5 is a horizontal section of the generator on the line 5—5 of Fig. 3 showing the supplemental external jet burners 14 in the walls of the burner so as to direct the gas jet downward upon the head of the generator. Fig. 6 is a vertical section 70 of the burner showing the downward jet burners. Fig. 7 is a like section showing the upward jet burners.

A body comprises the burner and the generator and has a central bottom opening 75 within which is secured the upper end of a mixing tube 1, and from which it depends, while the burner 2, is integral with the body and has the usual foraminous cap 3. The generator instead of being solid forms a large 80 space 4, into which the mixing tube opens, and which is extended to the burner cap, the object of which is to receive the partially mixed air and gas from the mixing tube and complete the mixture in a large volume to 85 give not only a better supply to the burner, but a richer mixture than can be formed in the mixing tube, because the volume the mixing space contains will form a reserve supply for the burner and give a more steady 90 light than can be obtained from the mixing tube only.

The vapor supply pipe 5, is secured to and depends from the bottom of the generator at one side of the mixing tube and terminates 95 below the open end thereof in a bend 6, which is provided with the usual vapor nozzle 7, and adjustable needle-valve 8, centrally in vertical alinement with the mixing tube to regulate the flow of the vapor from the generator into the mixing tube. For this purpose the open end of the mixing tube terminates a short distance above the needle-valve so that the vapor issuing therefrom under the

pressure caused by the vaporization of the oil in the generator, will, in being injected into the mixing tube, carry with it free air which is mixed with the gas in their passage up through the tube. An oil supply pipe 9, leads from an elevated reservoir (not shown) and enters the generator in communication with a duct 10, which, rising to the top of the generator, passes by an angle part and connects with a duct 11, which passes down and terminates in the upper open end of the vapor supply-pipe. In this course of the oil it is vaporized by the heat of the generator and is caused by pressure produced by such vaporization, to be forced down the vapor supply-pipe and ejected therefrom into the mixing tube. These oil supply and vapor connections are grouped so as to produce the quickest and best effect in the generator head under heat applied externally by a torch, for generating gas within the ducts; and it also gives the advantage of causing the generator part of the head to maintain a uniform degree of heat and a comparatively short flow of the oil to effect its vaporization. This is a matter of much importance in using the lamp for street lighting in the winter months. The outer walls of the burner chamber has a circumferential rim 12, which overhangs the top of the generator head, at the top of which beneath the rim, are formed jet openings 13, which open into the top of the large mixing space and are supplied therefrom with upward jets of vapor which impinge upon the rim and thereby form a supplemental burner around the burner-chamber for keeping it heated and for causing the heat to rise around the outer side of the burner heating the walls of the large vapor containing space and causing the vapor to be highly heated.

For increasing the generating capacity of the vaporizer we provide a second group of jet openings 14, in the walls of the burner chamber so as to pass laterally through the burner wall rim and open at the under side of the circumferential rim and project jets of gas from the burner chamber down upon the head of the generator and when ignited serve to heat the chamber walls of the generator and the chamber walls of the burner, because the downward projected jet flames striking upon the top abutment of the generator, will be caused to be deflected upward against the burner walls. The importance of this downward jet flame provision is that gas is supplied direct from the burner chamber wherein the gas in full volume and under full pressure is caused to pass out of the wall openings laterally without affecting the supply to the burner, and for this purpose a plurality of openings are made in the burner walls through the external rim. The ducts and the jet openings are made by borings in the walls and plugged at their outer ends. It

will be noted that the large space formed by the burner and the generator walls supplies the mantle and the external flame jets. It will be understood that the combustible vapor passes through the foraminous cap to the mantle which is mounted upon the burner.

Vapor burners of the character herein described can only be rendered successful in the winter months for street lighting by maintaining the vaporizing body under heat sufficient to generate a continuous supply of vapor, and for this purpose we have found that the vapor jets openings 14, in the walls of the burner chamber arranged to be ejected downward upon the head of the generator between the upward vapor jet openings 13, in the generator-head, in the effect of their combined heat, give the best results in producing and maintaining a constant heat sufficiently high to maintain a flow of the vapor through the vaporizing ducts; and it is the large vapor supply chamber that extends from the end of the mixing tube to the burner cap, that renders possible the supply of these upward and downward external separate groups of jet-flames without impairing the sufficiency of the volume for supplying the burner. When both groups of the external jets are used the flame from each group impinges upon different parts of the burner-head and in proportion to the heat produced thereby, will the supply of vapor be produced and maintained. As the upward and downward jets are supplied and maintained from the same volume of vapor and under the same pressure, they must be maintained as long as the oil supply continues; and the proximity of both sets of jet-flames conduces to the utilization of their combined heat in maintaining the heat of the generator.

In Fig. 5 is shown the relation of the downward jet opening 14, to the upward jet openings 13, so that the jets from one group will be between the jets of the other group. In such relation the jets from the lower group of openings will be projected into and mix with the jets from the upper group of openings; while the circumferential rim of the burner will form an impinging deflector for the upward jets and the top surface of the generator will form an impinging abutment for the downward jets, whereby one group of jets will reinforce the other group, and form an external unbroken flame with the advantage of increasing the heat of the generator and rendering certain the maintenance of an unbroken flame and the ignition of one group of jets by the other which is the important matter to effect the constant vaporization of the oil by a high heat of the walls of the oil ducts. In this operation the heat produced by the externally applied torch will take some time to heat the lower portion of the

device so as to vaporize the oil in the supply pipe 5, and the vapor will pass therefrom under a comparatively light pressure into and through the mixing pipe into the expansion 5 chamber and through and out of the burner. This upward flow of the vapor will have sufficient pressure in the expansion chamber to cause it to pass up through the jet openings 13, and be lighted, but the vapor in the 10 burner chamber would not at this time have sufficient pressure to cause the vapor to be forced out of the perforations 14, in the burner wall rim. As the pressure in the burner chamber however gradually increases 15 until it is approximately equal to that in the expansion chamber the side jet openings 14 would then supply the downward jets which would be ignited by the upward jets.

The advantage of using the circumferential rim of the burner as the means of supplying the downward jets is, the perforations formed through the rim serves to give the downward direction to the jets outside of the vertical burner wall and upon the head of the 25 vaporizer.

We claim:

In an incandescent vapor burner, a vapor generator including a burner having vertical walls and a mixing chamber; the walls of the mixing chamber having a group of openings 30 supplying upward external flame jets; the vertical walls of the burner having a group of openings above said chamber supplying downward external flame jets; both groups of openings being supplied from the mixing 35 chamber; one group directing its jets upon the wall rim of the burner and the other group directing its jets upon an abutment of the generator; the jets of one group mixing with the jets of the other group to form an 40 unbroken heating flame for the generator.

In testimony whereof we have signed our names to this specification in the presence of two subscribing witnesses.

JOHN C. HEINRITZ.
JAMES W. McCUEN.
